UNITED STATES PATENT OFFICE.

LORA E. POOLE, OF ANDERSON, INDIANA, ASSIGNOR TO DELCO-REMY CORPORATION, OF DAYTON, OHIO, A CORPORATION OF DELAWARE.

ARMATURE-CORE-INSULATING MACHINE.

Original application filed April 24, 1926, Serial No. 104,404. Divided and this application filed January 28, 1928. Serial No. 250,283.

This invention relates to the manufacture of armatures for dynamo electric machines, and particularly to the insulation of the armature core slots and of the conductors located within these slots.

The present invention is a division of application Serial No. 104,404 filed April 24, 1926, for an armature core insulation machine, comprising means for rotatably supporting a slotted armature core, means for folding a flat strip of insulating material into such form that it may be passed into the slots of the armature core and will there provide insulating recesses extending longitudinally of the core for receiving the conductors which are received by the slots of the core, means for automatically feeding the folded insulation strip into the core, means for severing that portion of the strip within the core from the remainder, and means for intermittently rotating the core in order to locate its various slots in alignment with the free end of the folded insulation strip.

It is particularly an object of the present invention to provide a novel method and apparatus for folding a flat strip of insulating material for the purpose specified in the foregoing paragraph.

Further objects and advantages of the present invention will be apparent from the following description, reference being had to the accompanying drawings wherein a preferred embodiment of one form of the invention is clearly shown.

In the drawings:

Figs. 1 and 2 are fragmentary plan and side elevations respectively of apparatus for folding a strip of insulating paper according to the present invention.

Figs. 3 to 10 are fragmentary sectional views taken on the lines 3-3 to 10-10 respectively of Fig. 2.

Fig. 11 is a sectional view on the line 11-11 of Fig. 1.

Fig. 12 is a fragmentary side view of a mechanism for intermittently rotating the feed rolls and is partly in section, the section being taken on the line 12-12 of Fig. 13.

Fig. 13 is a sectional view on the line 13-13 of Fig. 2.

Fig. 14 is a sectional view on the line 14-14 of Fig. 13.

Fig. 15 is a sectional view on the line 15-15 of Fig. 13.

Fig. 16 is a sectional view of a collet chuck.

Fig. 17 is a sectional view of a device to push the insulation into the armature slot after it has been severed.

Fig. 18 is an end view of the armature looking in the direction of the arrow 18 in Fig. 17.

Referring to Figs. 3 to 10 inclusive, the method of folding the paper to form slot insulation pieces will first be described. The flat strip of paper designated by numeral 20 in Fig. 3 is unwound from a supply roll (not shown) and is passed over a trough 21 which pivotally supports a weight member 22 tending to maintain the paper 20 flat within the trough. The paper is drawn from left to right as viewed in Fig. 2, and when it arrives approximately at the plane 4-4 of Fig. 2 it is passed between members or dies 23, 24, 25 and 26 where its cross sectional shape 20^a becomes one which is similar to a slanting N. When the paper arrives at the section plane 5-5 of Fig. 2 it will pass between members 23, 27, 28 and 29, which causes the paper to be folded so that its cross sectional shape 20^b resembles that of a slanting N having less inclination to the vertical than in Fig. 4. It will be noted that the part 23 in Fig. 5 is the same member as part 23 in Fig. 4 but its cross sectional contour gradually changes from that shown in Fig. 4 to that shown in Fig. 5 in order that the paper will be given a different shape as it progresses from the left toward the right. When the paper strip arrives at the plane 6-6 in Fig. 2 it passes between forming and feeding rolls 30 and 31 which give it the cross-sectional shape 20^c which might be characterized by likening it to an inverted U joined to an upright U or to a recumbent S. After the paper leaves the rolls 30 and 31 it passes into a flaring mouth 32 of a tunnel or die 33 which is oblong in cross-sectional shape with rounded ends as shown in Fig. 7. This tunnel 33 is provided by grooving two blocks 34 and 35 and placing them together as shown. The movement of the strip through the tunnel causes its shape to change from its cross sectional shape 20^c to the cross-sectional shape 20^d, the latter shape resembling

a relatively narrow upright S or a reversed S according to the direction in which the view is taken. After leaving the tunnel 33 the strip passes through a guide passage 36 5 provided in a rotatable work holder 40 which receives and supports an armature core 37 carried by a shaft 38 and provided with a plurality of slots 39. As the strips 20 are inserted into the slots 39, they are maintained 10 in contact with the bottoms of slots, for a purpose to be described later, by band 37^a which is placed temporarily around the armature core 37. The band 37^a is provided on its interior with longitudinally extending 15 ribs 37^b which are spaced so that each will be received by a core slot 39.

Referring to Fig. 11, the work holder 40 is a cup-shaped member having a horizontally disposed shank 41 rotatably supported 20 by a bearing 42 attached to a bracket 43 which is mounted upon the base plate 44 of the machine. Endwise movement of the shank 41 is prevented by the engagement with the bearing 42 of a shoulder 45 provided by the shank 41 and by a nut 46 engaging the threaded end 47 of the shank. The shank 41 is tubular and receives a rod 48 having a central recess 49 for receiving the armature shaft 38. The recess 49 is 30 rounded by three resilient spring arms 50 integral with the rod 48. These arms cooperate with an internal conical surface 51 provided by the shank 41. Thus the shank 41 and the resilient members 50 constitute 35 a collet chuck for gripping the shaft 38 when the rod 48 is pulled toward the left so that the ends of the chucking jaws 50 will be forced against the conical surface 51 and will grip the shaft 38. The rod 48 40 is threadedly connected with a flanged nut 52. A spring 53 located between the nut 52 and the nut 46 urges the rod 48 toward the left so that the shaft 38 will be gripped by the members 50. In order to release the 45 chuck so that the core and shaft may be removed from the machine, the operator will press a pedal (not shown, but connected with a lever 54) causing it to move in a clockwise direction. Levers 54 and 56 are 50 attached to a shaft 55 supported by the base 44. Lever 56 is provided with a hole 57 which receives a pin 58 connected with a plate 59 which is adapted to bear against the nut 52. Obviously, downward movement 55 of the lever 54 will be transmitted through the shaft 55 and the lever 56 causing it to move toward the right in order to compress the spring 53 and relieve the chucking jaws 50 from wedging engagement with the shank 41. The interior of the cup 40 is provided with a rib 60 which will be received by one of the core slots in order to locate the core properly relative to the work holder. 60

65 The trough 21 is supported by a bracket

65; and the guides 34 and 35 are supported by a bracket 66 and the bracket 43.

The feeding and folding rolls 30 and 31 are drivingly connected with shafts 70 and 71 respectively and are maintained in driving engagement therewith by nuts 72 and 73 respectively, engaging threaded ends of the shafts. The shaft 70 is journaled in bearing blocks 74 which are supported for vertical sliding movement by a bracket 75 supported by the base plate 44. Each bearing block 74 is yieldingly urged downwardly by spring 76 which bears at its upper end against a washer 77 bearing against a nut 78 threadedly connected with a rod 79 having its lower end connected with a plate 80 which is attached by screws 81 to the bracket 75. The lower end of the spring 76 bears against a disc 82 having studs 83 connected therewith, each stud 83 passing through a hole 84 in the plate 80 and bears at its lower end against the block 74. The shaft 71 is supported by bearings 85 carried by the bracket 75 and is drivingly connected with the shaft 70 by gears 86 and 87 connected respectively with shafts 71 and 70. The shaft 71 is supported also by bracket 88 mounted on the base plate 44.

The mechanism for imparting intermittent rotary motion to the shaft 71 in a clockwise direction as viewed in Fig. 12, comprises a ratchet 90 attached to the shaft 71 and engageable with a plurality of pawls 91 each mounted on a stud 92 supported by a disc 93 which is rotatably supported by the shaft 71 but is not drivingly connected therewith. Each pawl is urged toward the ratchet by a leaf spring 94 fixed at 95 to the periphery of the disc. The disc 93 is oscillated by a link 96 connected at one end with the disc and at the other end with a lever 97 rotatably supported by a stub shaft 98 carried by bracket 99 which is supported by the base 44. The lever 97 carries a cam following roller 100 which is received by a slot 101 of a drum cam 102 which is mounted on a shaft 103. Obviously, for each rotation of the shaft 103 there will be one complete oscillation of the lever 97 and link 96. This movement will produce rotation of the feed rollers 30 and 31, then a backing up of the pawls by movement in a counterclockwise direction preparatory to the next feeding operation. The ratchet 90 is prevented from backing up by a friction device including a drum 104 attached to the shaft 71 and engaged by a split clamping band 105 which is prevented from turning by the engagement of one of its lugs 107 with a post 106 attached to the base 44. The band 105 is urged into frictional engagement with the drum 104 by a spring 108 bearing against a lug 109 of the clamp and the head of a screw 110 which passes through plain holes in the lugs 107 and 109 and threadedly en-

gages the post 106. Turning the screw 110 will vary the friction pressure exerted by the clamp 105.

Due to the rotation of the rollers to feed 5 the paper endwise as well as to perform one of the steps of forming it, a portion of the strip of paper is fed through one of the 10 guide passages 36 in work holder 40 into an armature core slot 39 in alignment therewith. This portion is severed from the remainder of the strip by means including a shear block 150 which cooperates with a 15 slideable knife 151 which is guided by a bracket 152 attached to the bracket 43. 20 Soon after the end of the paper feeding operation, the knife 151 will shear the paper at the adjacent edge of the shear block 150.

After the shearing operation, the operation 25 of rotating the work holder 40 in a counterclockwise direction, as viewed from the right of Fig. 11, is performed in order to bring the next core slot 39 opposite the tunnel 33. It will be understood that the shear block 150 is provided with a groove 30 forming an extension of the groove in the block 33 so that the blocks 34 and 150 may cooperate with the block 33 to provide a tunnel forming an extension of the tunnel provided by the blocks 33 and 34 as de- 35 scribed with reference to Fig. 7.

It is therefore apparent that each cycle of 40 operation of the machine includes feeding a folded strip of paper into an armature core slot, the severing of that portion of the 45 paper within the armature core from the remaining portion, and the turning of the armature core relative to the paper feeding means in order that the next core slot to be insulated will be brought into alignment 50 with the passage 33 through which the insulation strip is guided into the armature core. During the feeding operation, a portion of the strip of paper is being folded preparatory to being fed into the armature 55 core during a succeeding feeding of the operation. The machine will operate continuously until all of the armature core slots have been provided with insulation pieces.

Referring to Figs. 2 and 11, it will be apparent 60 that it is not practical to locate the cutting edge of the knife bar 151 in the same plane as the left hand end of the armature core 37; therefore a portion of the strip 20^d measured by the distance between the plane 65 of the cutting edge of the knife bar and the plane of the left hand end of the armature core will project beyond the left hand end of the bar. It is desirable to shove substantially all of the insulation pieces 20^d through 70 the core slots in order that the ends of the strips may be received by closed slots 190 located in alignment with the slots 39 of the armature core and provided in a non-conducting disc 191 located adjacent that end 75 of the armature core which is to be remote

from the commutator. The function of the disc 191 is to assist in maintaining the armature conductors within the core slots. The insulating disc 191^a which is placed against the end of the core which is to be adjacent 80 the commutator may have open slots, since the soldered connections between the armature conductors and commutator risers will suffice to retain the conductors at the commutator end of the core. After each insulating strip 20^d has been pushed through the core so that its right hand end will be received by a closed slot 190 of the non-conducting disc 191 that end will be prevented 85 from coming out of the armature core. It will now be apparent that the ring 37^a will facilitate movement of the insulation pieces through the closed slots of the end non-conducting disc 191, since the ribs 37^b provided by the ring 37^a maintain the strips 20^d 90 against the bottoms of the core slots 39. After the strips 20^d have been moved past the shear block 150 they are shoved further toward the right in Fig. 11 by means including a bar 192 (see Fig. 2) which is slidably 95 supported by guide block 193 for endwise movement parallel to the direction of movement of the strip 20^d. Endwise movement of the bar 192 toward the strips 20^d in order to push them further into the armature core 100 is produced by a plate cam 194 having a beveled surface 195 which cooperates with a beveled surface 196 which defines a notch 197 with which the bar 192 is provided for receiving the cam 194.

By a suitable mechanism (not shown) the cam 194 is moved upwardly as viewed in Fig. 2 in order to move the bar 192 toward the right. A spring 199 which is located between a stationary block 193 and a shoulder 200 of a rod 201 connected in any well known manner not shown with the bar 192, tends to move the bar toward the left.

In order to facilitate threading the end 110 of the paper strip after it leaves the feeding and folding wheels 30 and 31 into the tunnel 33 between the blocks 33 and 34 as shown in Fig. 1, the guide block 33 is mounted to rotate about a vertical pivot stud 210 which is supported by the bracket 43. The guide 115 block 33 is maintained in the position shown by a U-shaped clip 211 having its branches engaging its vertical outsides of the guide blocks 33 and 34.

While the form of embodiment of the present invention as herein disclosed, constitutes a preferred form, it is to be understood that other forms might be adopted, all coming within the scope of the claims which follow.

What is claimed is as follows:

1. The method of making armature core slot insulation pieces from a flat strip which consists in progressively changing its cross-sectional shape from flat to N-shape and from N to that of a U joined to an inverted 120 125

U, and in compressing the U portions in a direction transverse to the axes of the U's while permitting the work to elongate in the direction of the axes of the U's, whereby 5 to form a piece having a cross-sectional shape which resembles a vertically elongated S.

2. The method of making armature core slot insulation pieces which comprises folding 10 a flat piece into one having a cross-sectional shape resembling a U joined to an inverted U, and in compressing the U portions in a direction transverse to the axes of the U's while permitting the work to 15 elongate in the direction of the axes of the U's whereby to form a piece having a cross-sectional shape which resembles a vertically elongated S.

3. Apparatus for making armature core 20 slot insulation pieces from flat material comprising, in combination, folding devices which gradually change the cross-sectional shape of the work from flat to N-shape, devices for changing the cross-sectional shape 25 of the work from the N-shape to that of a U joined to an inverted U, and devices for compressing the U-portions in a direction transverse to the axes of the U's while permitting the work to elongate in the direction 30 of the axes of the U's, whereby to form a piece having a cross-sectional shape which resembles a vertically elongated S.

4. Apparatus according to claim 3 in which the U forming devices include a plurality of rolls between which the material is gripped and is caused to move endwise relative to the other forming devices.

5. Apparatus according to claim 3 in which one of the sets of shaping devices includes 40 a pair of rolls between which the material is gripped and is caused to move endwise relative to the other forming devices.

6. Apparatus according to claim 3, in which one of the sets of shaping devices includes 45 a pair of resiliently mounted rolls between which the material is gripped and

7. Apparatus for making armature core slot insulation pieces from flat material 50 comprising, in combination, driving means, folding dies which change the cross-sectional shape of the work from flat to N-shaped, feed and forming rolls driven by the driving means feeding the material 55 through the dies and forming the N-shape to that of a U connected to an inverted U and dies for compressing the U-portions in a direction transverse to the axes of the U's while permitting the work to elongate in 60 the direction of the U's, whereby to form a piece having a cross-sectional shape which resembles a vertically elongated S.

8. Apparatus according to claim 7 in which the driving means are intermittently 65 operated.

9. Apparatus for making armature core slot insulation pieces from a web of flat material comprising, in combination, folding devices which gradually change the cross- 70 sectional shape of the work from flat to N-shape, feed and forming rolls feeding the work through the folding devices and forming the N-shape to that of a U connected to an inverted U, driving means for said feed 75 rolls, devices for compressing the U-portions in a direction transverse to the axes of the U's while permitting the work to elongate in the direction of the axes of the U's, whereby to form a cross-sectional shape 80 which resembles a vertically elongated S, and means for severing the work into core slot insulation pieces.

10. Apparatus according to claim 9 in which the driving means intermittently 85 drive the feed rolls and in which the severing means is a reciprocating blade operating during the rest period of the feed rolls.

In testimony whereof I hereto affix my signature.

LORA E. POOLE.
